United States Patent Office.

ETIENNE BOILEAU AND CHARLES MESNIER, OF ST. LOUIS, MISSOURI.

Letters Patent No. 88,122, dated March 23, 1869.

IMPROVEMENT IN BUT-HINGES.

The Schedule referred to in these Letters Patent and making part of the same.

To all whom it may concern:

Be it known that we, ETIENNE BOILEAU and CHARLES MESNIER, both of St. Louis, in the county of St. Louis, in the State of Missouri, have invented a new and improved Mode of Making Shutter-Hinges; and we hereby declare that the following is a full and exact description thereof, reference being had to the accompanying drawings, and to the letters of reference marked thereon.

The nature of our invention consists in making the hinge as shown in Figure A, to have the upper portion B act up as a cap, to be used either right or left, and so as to cover the pivot, and protect it from rain or damp.

The other part of the hinge C is bearing the pivot, and is also made to be used right or left.

The ring, or ferrule, marked D, is so arranged that in reversing it, it will fasten the shutter to the walls when open; also to fasten when the shutters are closed.

What we claim as our improvement in a shutter-hinge, is—

The ferrule, or ring D, having the notches E E', combined and arranged with the wings B and C of the hinge, the latter having the lugs G G', whereby the hinge may be used either right or left, and the shutter fastened both open and closed, all as described and shown.
